UNITED STATES PATENT OFFICE

2,617,001

ELECTRIC HEATING

Frederick E. Hasley, Wilkinsburg, Pa., assignor to
 Edwin L. Wiegand Company, Pittsburgh, Pa.,
 a corporation of Pennsylvania

Application August 30, 1950, Serial No. 182,370

8 Claims. (Cl. 201—63)

1

My invention relates to electric heating, and the principal object of my invention is to provide a suitable method of electroplating sheathed resistor electric heaters without damage from the plating solution.

In the drawing accompanying this specification and forming a part of this application I have shown, for purposes of illustration, two arrangements suitable to carry my invention into practice, and in this drawing:

Figure 1 is a section through a heater of the cartridge type, showing one arrangement suitable to carry my invention into practice; and

Figure 2 is a section through the terminal portion of a heater of the tubular type, showing another arrangement suitable to carry my invention into practice.

The heater 10 shown in Figure 1 comprises an electrically insulating core 11 commonly of ceramic material, a helical resistor 12 disposed on the core 11, a metal sheath 13 surrounding the core 11 and closed at its rear end 14, and refractory cement 15 disposed within the sheath 13, embedding the resistor 12, and serving both to insulate the resistor and to conduct the heat from the resistor to the sheath.

In this particular heater extensions of the resistor 12 are intertwisted with additional strands, forming the terminals 16 and 17, and these terminals are passed through apertures 18 and 19 in the body of the core 11 and emerge through the open end 20 of the sheath 13.

The heater 30 indicated in Figure 2 comprises a tubular sheath 31, a helical resistor 32 extending longitudinally of the sheath 31, projecting terminal pins 33 to which the ends of the resistor 32 are suitably attached, and compacted refractory material 34 such as magnesium oxide, embedding the resistor 32 and serving both to insulate the resistor and to conduct the heat from the resistor to the sheath.

As will be understood, the above two heaters are merely examples, and in undertaking to electroplate any form of heater, if the plating solution reaches the refractory material the heater is at least seriously damaged and usually completely ruined.

To avoid this result I introduce into a space 40 at each open end of the heater 10 or 30, a body of matter 41 sufficiently resistant to the plating solution, and of sufficient thickness, whereby the body 41 normally will not become trans-penetrated by the plating solution in the course of the time during which the heater is exposed to the solution.

2

At the present time I consider most satisfactory for this purpose a suitable uncured silicone rubber, such as the product known as "Silastic 120," preferably having admixed a quantity of a substance suitable as a filler, for example, zircon ground to as fine as 100 mesh or finer.

Obviously the proportions in which the filler may be added, will vary with the particular materials employed, including the specific weights, 10 but with the particular ingredients above stated by way of example, apparently the zircon should not be greater than twice the amount of the silastic, by weight, and preferably is in the range of 40 to 60 per cent of the whole, depending somewhat on the viscosity of the silastic.

In practice I may apply merely a suitable quantity of the material 41, as shown in Figure 1, or I may include a suitable member such as the ceramic bushing 42 shown in Figure 2, serving 20 to reduce the quantity of the material 41 and also to assist in compacting the material 41 in the respective space 40.

With the indicated composition I find that a suitable baking normally increased the resistance to the penetration of the plating solution, for example, a baking at approximately 200° F. for approximately one hour.

After the heater has been plated, preferably the material 41, and the bushing 42 or other 30 member that may have been included, are removed from the heater, and if the heater is to be sealed, a further application is made.

On the other hand, in some instances the penetration of the solution may be so slight that such 35 removal is not necessary, depending partly on the particular solution to which the material has been subjected.

As will be understood by those skilled in the art, various changes may be made, within the scope 40 of my invention, therefore my invention is not to be regarded as limited to the present disclosure, and I claim:

1. The method of preparing a sheathed resistor electric heater, including a sheath having at least one opening therein, and a resistor element having at least one terminal accessible through the opening disposed in said sheath and embedded in an electric insulating heat transferring refractory material, for immersion in an electroplating solution for electroplating the sheath, which comprises closing said opening by introducing thereinto a body of matter consisting essentially of an admixture of a rubber-like material and a filler, the filler being of a size to pass 55 through at least a 100 mesh screen and the

amount of filler being not greater than twice the amount of rubber-like material by weight and being in the range of 40 to 60 per cent of the whole, and baking such admixture at a temperature of approximately 200° F. for approximately one hour to increase the resistance thereof to the trans-penetration by the electroplating solution.

2. The method of preparing a sheathed resistor electric heater, including a sheath having at least one opening therein, and a resistor element having at least one terminal accessible through the opening disposed in said sheath and embedded in an electric insulating heat transferring refractory material, for immersion in an electroplating solution for electroplating the sheath, which comprises closing said opening by introducing thereinto a body of matter consisting essentially of an admixture of a rubber-like material and a filler, the filler being of a size to pass through at least a 100 mesh screen and the amount of filler being not greater than twice the amount of rubber-like material by weight and being in the range of 40 to 60 per cent of the whole, and baking such admixture to increase the resistance thereof to the trans-penetration by the electroplating solution.

3. The method of preparing a sheathed resistor electric heater, including a sheath having at least one opening therein, and a resistor element having at least one terminal accessible through the opening disposed in said sheath and embedded in an electric insulating heat transferring refractory material, for immersion in an electroplating solution for electroplating the sheath, which comprises closing said opening by introducing thereinto a body of matter consisting essentially of an admixture of a rubber-like material and a filler, the filler being of a size to pass through at least a 100 mesh screen and the amount of filler being not greater than twice the amount of rubber-like material by weight, and baking such admixture to increase the resistance thereof to the trans-penetration by the electroplating solution.

4. The method of preparing a sheathed resistor electric heater, including a sheath having at least one opening therein, and a resistor element having at least one terminal accessible through the opening disposed in said sheath and embedded in an electric insulating heat transferring refractory material, for immersion in an electroplating solution for electroplating the sheath, which comprises closing said opening by introducing thereinto a body of matter consisting essentially of an admixture of a rubber-like material and a filler, the amount of filler being not greater than twice the amount of rubber-like material by weight and being in the range of 40 to 60 per cent of the whole, and baking such admixture to increase the resistance thereof to the trans-penetration by the electroplating solution.

5. The method of preparing a sheathed resistor electric heater, including a sheath having at least one opening therein, and a resistor element having at least one terminal accessible through the opening disposed in said sheath and embedded in an electric insulating heat transferring refractory material, for immersion in an electroplating solution for electroplating the sheath, which comprises closing said opening by intro-

ducing thereinto a body of matter consisting essentially of an admixture of a rubber-like material and a filler, the amount of filler being not greater than twice the amount of rubber-like material by weight, and baking such admixture to increase the resistance thereof to the trans-penetration by the electroplating solution.

6. The method of preparing a sheathed resistor electric heater, including a sheath having at least one opening therein, and a resistor element having at least one terminal accessible through the opening disposed in said sheath and embedded in an electric insulating heat transferring refractory material, for immersion in an electroplating solution for electroplating the sheath, which comprises closing said opening by introducing thereinto a body of matter consisting essentially of an admixture of a rubber-like material and a filler, and baking such admixture at a temperature of approximately 200° F. for approximately one hour to increase the resistance thereof to the trans-penetration by the electroplating solution.

7. The method of preparing a sheathed resistor electric heater, including a sheath having at least one opening therein, and a resistor element having at least one terminal accessible through the opening disposed in said sheath and embedded in an electric insulating heat transferring refractory material, for immersion in an electroplating solution for electroplating the sheath, which comprises closing said opening by introducing thereinto a body of matter consisting essentially of an admixture of a rubber-like material and a filler, and baking such admixture at a temperature of approximately 200° F. to increase the resistance thereof to the trans-penetration by the electroplating solution.

8. The method of preparing a sheathed resistor electric heater, including a sheath having at least one opening therein, and a resistor element having at least one terminal accessible through the opening disposed in said sheath and embedded in an electric insulating heat transferring refractory material, for immersion in an electroplating solution for electroplating the sheath, which comprises closing said opening by introducing thereinto a body of matter consisting essentially of an admixture of a rubber-like material and a filler, and baking such admixture to increase the resistance thereof to the trans-penetration by the electroplating solution.
